UNITED STATES PATENT OFFICE

FISHER L. BOYD, OF HAVERFORD, PENNSYLVANIA, ASSIGNOR TO NATIONAL FOAM SYSTEM, INC., OF PHILADELPHIA, PENNSYLVANIA; A CORPORATION OF DELAWARE

AUTOMATIC FIRE-EXTINGUISHING APPARATUS

Application filed March 23, 1928. Serial No. 264,044.

My invention relates to fire extinguishing apparatus which is adapted to be installed in buildings and which also is adapted to operate automatically for the extinguishment of a fire which may originate in a building or in any room of a building in which the means is located for discharging and distributing the fire-extinguishing material.

10 The general object of the invention is to provide means whereby upon the occurrence of a fire at any selected point, whether in a building or not, fire-extinguishing foam is produced and released to extinguish such fire.

15 It also is an object of the invention to provide a system of pipes having portions terminating in different rooms, which pipes have connection with foam-generating means 20 and with each other, associated with means whereby upon the occurrence of a fire in any one of such rooms the system is operated to produce fire-extinguishing foam which is delivered to such room and applied for the 25 extinguishment of the fire which may be present therein.

To these and other ends my invention comprehends the construction and arrangement as hereinafter described in detail, particularly pointed out in the claims, and as illustrated in the drawing wherein I have shown a construction which at present is that preferred by me. However, it will be understood that the invention is susceptible 30 of embodiment in other specific forms of construction than that shown and that changes in the details of construction and arrangement may be made within the scope 35 of the claims without departing from the 40 said invention or the principle involved therein.

In the drawing:

Fig. 1 is a plan view, partly schematic, of a construction embodying the invention, the walls of the rooms within a building within which portions of the construction are located being shown in sectional plan; and

Fig. 2 is a section taken on the line 2—2 of Fig. 1.

50 In the drawing I have indicated at 1 the

outer walls of a building divided by the transverse walls or partitions 2 into three separate rooms. Into these separate rooms pipes 3, 4, and 5 project, each of which pipes is provided with discharge nozzles indicated at 6, from which fire-extinguishing foam is adapted to be discharged into the particular room within which a particular pipe may be located. Each of these pipes also is connected to controllable means by which the fire-extinguishing foam-producing ingredients or elements are adapted to be supplied thereto so that the said foam is produced within the individual pipes which project into the respective rooms.

60 In the drawing the rooms are indicated as being of relatively small dimensions, so that a single pipe projecting thereinto is sufficient to supply the foam necessary for the extinguishment of a fire therein, but it will 65 be understood that in the case of larger rooms a plurality of pipes may be provided therein in order that the entire area of the room may be subjected to the action of the foam.

65 Each of the pipes 3, 4, and 5 is connected by branch pipes 7 and 8, 9 and 10, and 11 and 12 to a couple of pipes 13 and 14. These pipes at their outer ends are connected with a Y-shaped member 15, the tail of which is 70 connected to a water supply pipe 16 having connection with a source (not shown) of water supply. For the purpose of supplying the ingredients necessary to the production of fire-extinguishing foam I have provided hoppers 17 and 18, the first of which is 75 in communication with the pipe 13 and the second of which is in communication with the pipe 14. The form of connection is shown in Fig. 2 of the drawing. I shall 80 not describe in detail the construction of the connection between the hoppers and the pipes 13 and 14 nor the manner in which the material therein, which is in powdered form, is withdrawn therefrom into the pipes and 85 carried forward therein, because their construction and operation may be identical with that illustrated in Fig. 1 of my pending application for Letters Patent filed 90 March 2, 1927, Serial No. 177,988. However, 95 100

it will be understood that any other suitable means may be employed for containing and supplying the foam-producing ingredients separately to the pipes 13 and 14. The fire-extinguishing foam-producing ingredients employed in the respective hoppers may consist of any suitable known substances, but those generally used and which are preferred by me are aluminum sulphate in powdered form, of a fineness which will permit it to flow through a 40-mesh screen, and powdered bicarbonate of soda. With one or the other of these substances, or both, a stabilizing substance or substances may be employed. It is undesirable that the fire-extinguishing foam-producing substances be mixed prior to the time at which they are to be used and it will therefore be understood that these two substances, aluminum sulphate and bicarbonate of soda, are retained and are at all times present in the respective hoppers 17 and 18, ready to enter the respective pipes 13 and 14 as occasion may arise. For the purpose of controlling the supply of water from the supply pipe 16 to the Y-shaped fitting 15 and through the branches thereof to the pipes 13 and 14 I have provided a valve at 20, and for the purpose of controlling the flow of the liquid containing the substances, aluminum sulphate and bicarbonate of soda, in solution, from the pipes 13 and 14 to any one of the pipes 3, 4, or 5 I have provided valves 21 and 22 in the respective branch pipes 7 and 8, 9 and 10, and 11 and 12. The opening and closing of all of these valves is adapted to be automatically effected by means which will now be described.

For operating the various valves to which reference has been made electric current is relied upon. The current for this purpose is taken from the main supply lines 25 and 26, the former being indicated as positive and the latter as negative. Associated with the respective valves are electromagnets 27, 28, 29, 30, 31, 32, and 33. The circuits through these magnets are connected to the main lines 25 and 26 and are in parallel. The closing of the respective circuits is controlled by means of relays 35, 36, 37, and 38, which operate in known manner. The relays 36, 37, and 38 are connected to the respective branch circuits 40, 41, and 42 which extend through the respective rooms of the building, as shown, the said branch circuits being normally open, as indicated. For the purpose of closing the said circuits I have provided in association with each of them thermostatic closing means, indicated at 43. The thermostatic device or element consists of a strip of metal comprising two sheets secured together, which sheets expand unequally upon the application of heat thereto, as a result of which the said element bends 65 and in bending contacts with an opposing

stationary contact 44. The operation of thermostatic devices of this character is well known and in consequence I shall not describe the same more fully. Each of these thermostatic contact closing devices is identical and a description of one constitutes a description of all. It will be noted that there are four of these thermostatic contact closing devices associated with each of the branch lines 40, 41, and 42. Assume for the moment that a fire occurs in the room within which the pipe 3 is located, and assume that any one of the thermostatic contact devices is operated to cause a movable thermostatic element to contact with the stationary contact to close the branch circuit 40. Upon the closing of the said circuit current will flow from the line 25 through the circuit which includes the coil of the relay 36. The flow of current therethrough will close the relay 35 and permit current to flow through the branch circuit indicated as a whole at 45. This circuit includes the electromagnets 28 and 29, the energization of which causes the valves 21 and 22 to open. Simultaneously the relay 35 is closed as the result of current flowing through the coil of the magnet thereof. The closing of the said relay closes the circuit 46 through the electromagnet 27, the energization of which results in the opening of the valve at 20. Water therefore is permitted to flow from the pipe 16 through the Y-fitting 15 and thence through the pipes 13 and 14. The flow of water through these pipes effects the withdrawal of the powdered substance from the hoppers 17 and 18, to which reference has been made already. These substances are dissolved during the forward flow of the water in the pipes 13 and 14, and the valves 21 and 22 having been opened, the water flows through the branch pipes 7 and 8 and unites in the pipe 3. The uniting of the solutions of the respective substances results in the formation of foam, which is discharged from the nozzles 6. The discharge of this foam into the room where the fire is located results in the extinguishment of the fire in well known manner.

In like manner the relays at 37 and 38 are adapted to be closed upon the occurrence of a fire in either the room in which pipe 4 is located or the room in which pipe 5 is located. The tracing of the circuits may be made in exactly the same manner as has been made in connection with the relay 36 in the case in which a fire has been assumed to have taken place in the room within which the pipe 3 is located.

If fire should originate simultaneously in all of the rooms illustrated all three of the relays 36, 37, and 38 would be closed and the valves in the respective branch pipes 7 and 8, 9 and 10, and 11 and 12 would be opened with the simultaneous opening of the

valve at 20. This would result in the simultaneous supply of fire-extinguishing foam to all three of the rooms, or to a greater or less number in accordance with the design 5 of the apparatus to effect simultaneous extinguishment of the fire in all of the rooms.

It will be understood that the apparatus should be designed in accordance with engineering principles to meet the conditions 10 as to quantity of water to be supplied and as to other matters of a practical character well understood by engineers or other persons skilled in the subject matter to which the invention relates.

15 It will be seen that I have provided a system of fire protection of simple construction by the employment of which fire-extinguishing foam may be produced and supplied automatically to any room or to any 20 number of rooms of a building which may be included within the system. When the efficiency of foam for the extinguishment of fires is considered and realized the importance 25 of my invention, by means of which provision is made for the automatic application of foam in the manner as described, will be apparent.

Having thus described my invention, what I claim and desire to secure by Letters 30 Patent is:

1. Automatic fire-extinguishing apparatus for protecting buildings and the like, comprising single pipes located within the regions to be protected which pipes are provided 35 with discharge openings, a couple of pipes extending in distant relation to the said regions which are to be protected, sets of branch pipes connected to the said couple of pipes, the pipes of each of said sets uniting in one of the first-named pipes, means for supplying foam-producing substances to the respective pipes of the said couple of pipes, a valve for controlling the flow of water to the said couple of pipes, valves 40 for controlling the flow of water containing said foam-producing substances from said couple of pipes to the said first-named pipes, and means located within the respective regions to be protected by the apparatus, the means in any region adapted to be operated by the heat generated by a fire occurring in such region to open the valves to permit flow of water containing the said substances to and through the pipe in such region.

55 2. Automatic fire-extinguishing apparatus for protecting a building against fire, comprising pipes located at different points within said building, said pipes each being provided with a plurality of discharge openings, a couple of main pipes, branch pipes connected respectively to the said couple of pipes and also connected with each first-named pipe, a pipe for supplying water to the said couple of pipes, means for supplying foam-producing substances separately to

the pipes of said couple of pipes, valves for controlling the flow of water containing said substances through the said couple of pipes and from the latter through the said branch pipes to each first-named pipe, and means 70 common to the valves which control the flow of water containing said substances to any one of the first-named pipes for controlling the said valves to permit the flow of water containing the said foam-producing substances to such first-named pipes. 75

3. Automatic fire-extinguishing apparatus, comprising a plurality of pipes each extending into a room or other region which it is desired to protect from fire and each being provided with discharge openings through which fire-extinguishing foam is adapted to be discharged, a couple of pipes, branch pipes connected at intervals respectively to the said couple of pipes and to the 80 respective first-named pipes, means for supplying water to the said couple of pipes, a valve for controlling the flow of water into said couple of pipes, means for supplying foam-producing substances separately to the 85 said couple of pipes, valves for controlling the flow of water containing said foam-producing substances through the said couple of pipes and from the latter through the said branch pipes to the first-named 90 pipes, magnetic means for controlling the opening and closing of said valves, and means located within the respective regions to be protected by the first-named pipes adapted to be actuated by the heat generated 95 by a fire occurring in such regions to control the valve which controls the flow of water into the said couple of pipes and to control the valves of the branch pipes through which the water containing said 100 foam-producing substances flows from the said couple of pipes to the pipes located within the said regions. 105

4. Automatic fire-extinguishing apparatus for protecting any portion of a building 110 against fire, comprising a pipe located in the said portion to be protected which pipe is provided with openings through which fire-extinguishing foam is adapted to be discharged, a couple of pipes through which water containing substances in solution is adapted to flow, which solutions when united produce fire-extinguishing foam, a set of branch pipes which extend from the said couple of pipes to the said first-named 115 pipe, means for supplying water to the said couple of pipes, a valve for controlling the flow of water into said couple of pipes, means for supplying foam-producing substances separately to the respective pipes of the 120 said couple, valves for controlling the flow of water containing said foam-producing substances in solution from the said couple of pipes through the said set of branch pipes to the said first-named pipe, 125 130

means adapted to operate to open and close the said first and second named valves, and means located within the said portion of the building to be protected which is adapted to be actuated by the heat generated by a fire which may originate in said portion to actuate the said valve controlling means for opening said valves to permit the solutions of foam-producing substances to flow through the said branch pipes into the first-named pipe wherein the foam is produced by the uniting of the two streams of foam-producing solutions from the said set of branch pipes.

5. Automatic fire-extinguishing apparatus for protecting buildings and the like, the said buildings each comprising any number of rooms, the said apparatus comprising pipes which respectively extend into the said rooms, a couple of pipes located outside of a building to be protected, branch pipes connected to the said couple of pipes which branch pipes are arranged in couples, those of each said second mentioned couple being united in one of the first-named pipes, means for supplying water to the said first mentioned couple of pipes, a valve for controlling the flow of water into said first mentioned couple of pipes, means for supplying foam-producing substances to the respective pipes of the said first mentioned couple of pipes, valves for controlling the flow of water containing said foam-producing substances from said first mentioned couple of pipes through the said branch pipes to the first-named pipes, means for opening and closing the said first and second named valves, and means located within the respective rooms to be protected by the apparatus which means in said respective rooms is adapted to be operated by the heat of a fire occurring in a room to cause actuation of the valves for controlling the flow of water containing said foam-producing substances into and through the pipe located in the said room.

In testimony that I claim the foregoing as my invention I have hereunto signed my name this 22nd day of March, A. D. 1928.
